GAS BURNER WITH FLASH TUBE CHARGING PORT

Ervin H. Mueller, Grosse Pointe, Mich.

Application January 4, 1947, Serial No. 720,174

3 Claims. (Cl. 158—115)

1

This invention relates to gas burners and it has to do particularly with burners for gas ranges.

Gas ranges usually employ several burners which are sometimes referred to as top burners, these being adjacent a top portion or supporting surface of the range so that cooking vessels are supported above the burners. These burners are each supplied with the fuel comprising a mixture of air and gas by a mixing tube or venturi and in some cases it is desirable to have the mixing tubes in a plane below the burners. In this situation, the fuel passing to a burner through a mixing tube is caused to be turned so as to flow in an upward direction at about the time the gas enters the burner.

The automatic igniting means for the burners usually embodies a pilot flame positioned more or less centrally of several burners with flash tubes extending from the pilot flame to the burners, there being one flash tube for each burner. When gas is supplied to a burner, some of the gas is caused to flow through the flash tube where it is ignited at the end of the flash tube adjacent the pilot flame. This results in a flash-back or sort of explosion and ignites the gas issuing from the ports of the burner.

In order to furnish gas to the flash tube for each burner, there is provided a fitting commonly referred to as a tip which is engaged in a charging port in the burner. The tip conducts the gas from the port and directs it into the flash tube. A more or less standard type of tip is an element or fitting with a passage therein which is angular in form so that gas enters the same in an upward direction and is turned through substantially 90° and directed into the flash tube which extends substantially horizontally. Now, a difficulty arises when this sort of a lighter arrangement is used with a gas burner which is positioned above the mixer tube, particularly where the port for receiving the gas which is to cause the ignition is positioned in alignment with the upwardly extending part or upwardly opening mixer tube. In this case the gas is flowing directly into the port and due to its velocity as well as pressure, too much gas will enter with the result that an improper action is provided. The gas may even blow the pilot flame to such an extent that it may be extinguished. Yet, it is desirable to use a standard size tip so that the tips can be manufactured with uniformity, and can be interchangeable with all types of burners.

The present invention provides an improved arrangement whereby the charging port is provided with an ensmalled or reduced metering portion so that a standard type tip may be used. It is also an object of the invention to provide a burner which is arranged to lie above the mixer

2

tube with a spreader or baffle for controlling the flow of gas into the burner and make for a uniform flame condition throughout the circumference of the burner. Otherwise, an excess of gas may flow through the burner ports at a position immediately over the mixer tube while a lower volume of gas would be furnished the burner ports remote from the end of the mixer tube. The invention is disclosed in the accompanying drawing:

Fig. 1 is a general view showing two burners of a gas range and indicating the lighter arrangement.

Fig. 2 is an enlarged view, partially in plan, of a burner, with some parts cut away to show interior structure.

Fig. 3 is a view partially in side elevation with parts cut away and parts shown in section.

Fig. 4 is a cross sectional view taken substantially on line 4—4 of Fig. 2 showing the burner and lighter arrangement.

As illustrated in Fig. 1, a frame structure of a gas range is shown at 1, and it is provided with a top surface or plate 2 which lies over several burners, but which has openings 3 therein to expose the same. Two burners are shown, each generally indicated at 5, and each is supplied with gas through the means of a controlling valve 6 while the primary air for the mixture may be regulated by adjustable air control element 7. Extending from the air control element is the so-called mixer tube or venturi 8.

The burner structure, as shown in Figs. 2, 3 and 4, comprise a body portion 12 with a circular channel 13 therein. The body may rest upon a support 14 and one side of the body portion has a projecting flange like arrangement 15 for attachment to a corresponding flange 16 at the upwardly opening end of the mixer tube 8. This may be accomplished by means of screws 17. A burner cap 20 seats upon the burner body. This cap structure may be somewhat in the form of a ring so as to cover the channel 13 and provided with a spoked center having a screw 21 which is threaded into a cross bar 22 of the burner body, the cross bar providing openings 23 for secondary air. The cap is provided with a multiplicity of grooves 25 to provide ports when the cap is seated on the body, so that gas issues from the ports to support the gas flames. The inner peripheral portion of the cap may be provided with a suitable number of ports 26 also for the issuance of flame supporting gas.

Now, it will be noted that the upwardly opening end of the mixer tube is positioned adjacent one side of the channel 13 as will be appreciated by reference to Fig. 2 where the passage formed by the mixer tube and by the burner body is indicated at 30. Accordingly, some of the burner

ports which are immediately adjacent and above the passage 30 are liable to receive an excess supply of gas while those more remote therefrom may receive less. To meet this situation, the burner body is provided with a baffle or separator 31 which is positioned in substantial alignment and above the passage 30. This baffle may be a strut-like element formed integrally with the burner body and as shown in Fig. 3 has oppositely inclined surfaces 32 and 33. The upwardly flowing gas strikes these surfaces and is diverted laterally as indicated by the arrows so that the gas is directed into the channel 13 in opposite directions. This insures a substantially uniform supply of gas to each of the ports 25 and 26 by lessening the supply of gas through immediately adjacent ports and directing the gas into a stream in the channel 13 for supplying the remote ports.

The lighter structure has the flash tube 40, one end of which is positioned adjacent a pilot flame 41 in a housing or guard 42, there being a flash tube for each burner as shown in Fig. 1. The other end of the flash tube is provided with extending arms 43 secured in which is the tip. This tip may comprise a block of metal having a body portion 44 and a tapered extension 45 with an angular opening or passage 46 therethrough. The tapered portion 45 is designed to fit into a charging port 47 in the burner body. When gas is supplied to the burner, some gas flows through the charging port through the passage 46 and is directed to flow through the flash tube 40. This gas is ignited by the flame 41. There is a resultant flash-back which then ignites the gas issuing from the ports 25 which may, in turn, ignite the gas issuing from ports 26.

Now, it will be observed that the charging port 47 is in direct alignment with the gas flow passage 30 and due to the fact that the charging port 47 directly faces the on-coming velocity of the gas, there would normally be too great a flow of gas through the flash tube, which might blow the pilot flame 41 from its source and extinguish it. Yet, it is desirable to use a tip of standard size so that the portion 45 need not be varied and so that the tips may be used with all kinds of burners. To take care of this situation, the burner is provided with a metering port which is ensmalled relative to the port 47 to cut down the supply of gas entering the charging port. As shown in Fig. 3, this is provided by forming the charging port 47 only partially through the material of the body of the burner and by providing the ensmalled metering port 48 with the charging port 47 and which serves to reduce the gas supplied for ignition purposes. This is provided without requiring any additional manufacturing operations and the size of the port 48 may be selected to provide the desired igniting function under conditions encountered. Accordingly, a standard tip may be used in this type of construction which would otherwise require different structures and manufacture conditions for tips and the charging port therefor.

I claim:

1. In gas burning equipment, a burner body having ports for the issuance of flame supporting gas, a mixer tube for conducting gas to the burner, the burner body and mixing tube providing a gas passageway, a wall section disposed

partially across said passageway and defining an enclosing wall of said passageway, gas igniting means including a tip for a flash tube, said wall section having a charging port extending transversely therethrough for receiving the tip and for supplying gas thereto, said wall section extending generally transversely of the axis of said passageway so that the charging port is in substantially direct alignment with the direction of flow of the gas, whereby flow of gas into the charging port is influenced by both pressure and velocity, and means at the inlet end of said charging port providing an ensmalled metering port for the gas passing from said passageway to the tip to reduce the volume of gas passing to the tip to substantially offset the tendency of increased flow which would normally pass therethrough due to the velocity.

2. In gas burning equipment, a burner body having ports for the issuance of flame supporting gas and having a downwardly opening inlet passage, a mixer tube for conducting gas to the burner and having an upwardly opening outlet passage communicating with the inlet passage of the burner, the burner body having a wall section extending partially across the outlet passage of the mixer tube substantially horizontally and defining an upper enclosing wall for part of the tube, gas igniting means including a tip for a flash tube, said wall section having a charging port extending transversely therethrough for receiving the tip, whereby the flow of gas into the charging port tends to be increased due to the influence of velocity of flow, the burner body having an ensmalled metering port in the inlet end of the charging port of such a size as to reduce the flow of gas passing into the charging port to substantially offset the influence of velocity.

3. A gas burner comprising a body having ports in its upper portion for the issuance of flame supporting gas and having a passage for conducting the gas to the ports, said passage being positioned below the burner ports, the body having a wall section positioned substantially horizontally and constituting an upper enclosing wall for part of said passage, said wall section having a substantially vertically disposed charging port therein which opens upwardly and which is adapted to supply gas for ignition purposes, said wall section having an ensmalled metering port at the lower end of the charging port and connecting the said gas passageway and the charging port, said metering port being the only means of passage of gas from the said passageway to the charging port and serving to minimize the influence of the velocity of flow in the gas passage on the flow of gas into the charging port.
